UNITED STATES PATENT OFFICE.

JOHN COLWELL BYXBE, OF PENSACOLA, FLORIDA.

SHOULDER-REST FOR BUGGIES OR CARRIAGES.

SPECIFICATION forming part of Letters Patent No. 633,305, dated September 19, 1899.

Application filed June 14, 1899. Serial No. 720,531. (No model.)

To all whom it may concern:

Be it known that I, JOHN COLWELL BYXBE, a citizen of the United States, residing at Pensacola, in the county of Escambia and State of Florida, have invented a new and useful Shoulder-Rest for Buggies or Carriages, of which the following is a specification.

The invention relates to improvements in shoulder-rests for buggies and carriages.

10 The object of the present invention is to provide for buggies and carriages a simple, inexpensive, and efficient device designed to be readily applied to the back of a seat and to the rear bow of a buggy or carriage top and 15 adapted to afford a comfortable rest or support for the shoulders and capable of being readily removed when it is desired to lower the top of the buggy or carriage to which it is applied.

20 The invention consists in the construction and novel combination and arrangement of parts hereinafter fully described, illustrated in the accompanying drawings, and pointed out in the claims hereto appended.

25 In the drawings, Figure 1 is a side elevation of a portion of a carriage provided with a shoulder-rest constructed in accordance with this invention. Fig. 2 is a detail perspective view of the shoulder-rest. Fig. 3 is a detail 30 view of the catch for securing the front end of the arm-rest to the rear bow of a carriage-top. Fig. 4 is a detail view of the angle-plate which forms a socket for the arm of the rear end of the arm-rest.

35 Like numerals of reference designate corresponding parts in all the figures of the drawings.

1 designates a curved arm-rest designed to be constructed of any suitable material and 40 having its inner face rounded from its upper to its lower edge and presenting a flat rear or outer face which is straight in vertical section and curved in longitudinal section to conform to the general configuration of the 45 arm-rest. The arm-rests are designed to be constructed in pairs and to be arranged at opposite sides of a vehicle, and each arm-rest is provided at its front end with a catch 2 and at its rear end with an arm 3, which is adapted 50 to engage a socket 4 of the seat-back 5 of the vehicle. The arm 3, which is arranged at the rear end of the arm-rest, is substantially L-

shaped and engages an opening 6 of an angle-plate which forms the socket 4. The angle-plate, which fits against the upper and rear 55 faces of the seat-back, is perforated for suitable fastening devices and is provided at its top with the said opening 6. The depending portion of the arm is angularly bent between its ends to form a shoulder 7, which engages 60 the upper face of the socket, whereby the rear end of the arm-rest is supported thereon.

The rear arm 3 is preferably formed integral with a reinforcing bar or brace which extends longitudinally of and is secured to the rear or 65 outer face of the arm-rest, and the front end of the bar or brace is extended to form the fixed member 9 of the catch or clamp which secures the arm-brace to the rear bow 10 of the carriage-top. The fixed member of the 70 clamp is provided between its ends with a curved portion 11, disposed at a slight inclination to fit the inclined rear bolt and conforming to the configuration of the inner face of the same. The fixed member is locked in 75 engagement with the rear bolt by a pivoted movable member 12, which is adapted to engage the outer face of the bow. The movable member is connected with the outer end of the fixed member by a rivet 13 or other 80 suitable fastening device, and it is provided at its inner end with a notch 14, adapted to engage a headed stud 15, mounted on the outer face of the fixed member 9 and located adjacent to the front end of the arm-rest, as 85 clearly illustrated in Fig. 3 of the accompanying drawings. The inner or free end of the movable member of the clamp or catch is curved outward, as clearly shown in Fig. 2, to enable it to be readily grasped by the operator to swing it into and out of engagement with the headed stud in applying the arm-rest to a vehicle and in removing it therefrom. The rear end of the arm-rest is detachably 90 and rigidly interlocked with the seat-back, 95 and as the front end is firmly secured to the rear bow the device forms an efficient brace and is adapted to support the carriage-top, besides affording a comfortable rest for the shoulders.

100 The invention has the following advantages: The arm-rest, which is exceedingly simple and inexpensive in construction, possesses great strength and durability, and it is capable

- of being readily applied to vehicles of the general character illustrated in the accompanying drawings. It is adapted to afford a comfortable support for the shoulders of the occupant, and it forms an efficient brace for supporting the carriage-top. It may be readily removed when it is desired to lower the top of a carriage, and it is capable of being quickly arranged in position for use.
10. Changes in the form, proportion, size, and the minor details of construction within the scope of the appended claims may be resorted to without departing from the spirit or sacrificing any of the advantages of this invention.
15. What is claimed is—
1. A shoulder-rest for buggies and carriages extending from the seat-back to the rear bow and provided with means for detachably connecting it to such parts, substantially as and 20 for the purpose described.
  2. A device of the class described comprising a curved shoulder-rest arranged horizontally and provided at its rear end with means for detachably mounting it on the seat-back, 25 and a clamp or catch arranged at the front end of the arm-rest and adapted to engage the rear bow detachably, substantially as described.
  3. In a device of the class described, the 30 combination with a vehicle, of a shoulder-rest extending from the back of the vehicle to the rear bow and detachably engaging the latter, substantially as described.
  4. A device of the class described comprising a socket designed to be arranged at the 35 seat-back, and a shoulder-rest designed to extend from the seat-back to the rear bow, and provided at its front end with means for engaging the latter, said shoulder-rest being 40 provided at its rear end with a depending arm, detachably fitting in the said socket, substantially as described.
  5. A device of the class described comprising a socket designed to be mounted on the
- seat-back, a curved shoulder-rest provided at its rear end with an arm fitting in the said socket and having a shoulder for engaging the same, and a clamp or catch mounted at the front end of the shoulder-rest and adapted to engage the rear bow, substantially as described.
6. A device of the class described comprising a shoulder-rest designed to be mounted at its rear end on the seat-back, and a clamp or catch arranged at the front end of the shoulder-rest and comprising a fixed member having a curved portion to receive the rear bow, and a movable member pivoted to the fixed member at one side of the curved portion thereof and detachably engaging a projection 60 at the opposite side of the curved portion, substantially as described.
7. A device of the class described comprising a shoulder-rest, a bar or brace secured to the outer face of the same and extended beyond the ends thereof, one end of the bar or brace being L-shaped and the other end being provided with a concave portion, a socket adapted to receive the L-shaped end of the bar or brace, and a pivoted member mounted 70 on the other end of the bar or brace, substantially as described.
8. A device of the class described comprising an angle-plate provided with a slot, a shoulder-rest provided at its rear end with an 75 L-shaped arm engaging the slot of the angle-plate, and a clamp or catch arranged at the front end of the shoulder-brace and adapted to engage the rear bow of a carriage-top, substantially as described.

In testimony that I claim the foregoing as my own I have hereto affixed my signature in the presence of two witnesses.

JOHN COLWELL BYXBE.
